UNITED STATES PATENT OFFICE.

EMIL GATHMANN, OF BALTIMORE, MARYLAND.

INGOT-MOLD.

1,209,283.

Specification of Letters Patent. Patented Dec. 19, 1916.

Application filed June 29, 1916. Serial No. 106,601.

To all whom it may concern:

Be it known that I, EMIL GATHMANN, a citizen of the United States, residing in the city of Baltimore, State of Maryland, have 5 invented certain new and useful Improvements in Ingot-Molds, of which the following is a specification.

This invention relates to improvements in the construction of ingot molds of the class 10 in which the larger part of the mold is uppermost. Molds of this kind are generally open at both top and bottom, the bottom being closed while casting either by means of a stool on which the mold rests and which is 15 sometimes provided with a short projection which enters the opening in the bottom of the mold, or by what is known as a stripping plug which serves the double purpose of sealing the bottom opening and of also detaching 20 the ingot from the mold at the commencement of the stripping operation.

The object of my present invention is to 25 efficiently seal the bottom portion of the mold chamber in such manner as to prevent the escape of molten metal therefrom.

In the accompanying drawings, Figure 1 shows a vertical central section through an ingot mold with my improvements applied thereto. Fig. 2 is a perspective view of the 30 sealing plate employed. Fig. 3 is a detail view on an enlarged scale of the lower portion of the mold showing how the bottom opening thereof is sealed.

The mold A may be of usual construction 35 but is preferably of the kind shown, i. e., a big-end-up mold having its walls thicker in the lower portion than in the upper portion thereof for purposes now well understood. The lower portion of the mold cavity is 40 shown as being necked-in toward the bottom opening α of the mold and this necked-in portion is curved or concaved, the radius of the concave being preferably less than one-half the diameter of the mold at its lower 45 portion above said necked-in part. This is indicated at α' . The walls of the bottom opening of the mold may be of any suitable shape but where the walls of the bottom opening join the concaved walls α' there is a 50 rounded portion b^2 , the radius of which, as indicated in the drawing, is relatively short. In this way the concaved walls gradually merge into the walls of the bottom opening of the mold and the sticking of the ingot in 55 the mold at its lower end is prevented. If

the portion a^2 were angular the molten metal would be apt to cut into the mold walls and form a recess or recesses where the metal would enter and thus form keys or stickers which would impede the stripping operation. 60 Furthermore, by reason of the form given to the lower portion of the mold the molten metal while being poured will spread side-wise against the concaved portions α' and will be directed upward and thus lessen the 65 liability of forming stickers. If the molten metal strikes the portions α' while being poured it will be directed inward toward the center of the mold. Should the walls α' be worn away during the pouring of the 70 molten metal the formation of stickers or re-entrant angles would not occur.

The bottom opening of the mold may be sealed in various ways. As illustrated the bottom opening is filled by a stripping plug 75 B which fits the opening somewhat loosely. In some cases it may be made to fit the opening tightly but as a rule there should be rather a loose fit. After the ingot is cast the stripping plug is used to raise the ingot in 80 the mold, after which the top of the ingot is taken hold of by lifting devices which remove it from the mold.

Inasmuch as in many cases the stripping plug fits the bottom opening of the mold 85 loosely, it is desirable to employ some means for so sealing the opening that molten metal will not run down between the sides of the stool and the walls of the bottom opening in such manner as to cause the stool to adhere 90 to the mold and thus prevent it from being moved freely while stripping. The sealing device which I employ in my present invention consists of a plate C of sheet metal which is preferably flanged at c as 95 shown. The edge of the plate rests on the bottom wall of the mold cavity, preferably on the rounded portion a^2 and preferably the rim c is curved to correspond with the rounded portion a^2 so as to fit it in the 100 manner indicated in the drawings. In this way I am able to obtain a seal sufficiently secure without the use of refractory material such as is often used for sealing purposes. I do not mean to say that my invention excludes the use of such refractory material, but it is not necessarily employed. Where refractory material is used gases 105 are apt to be formed which enter the molten metal and impair its quality. When the 110

ingot is cast the plate C adheres to the lower end of the ingot and passes out of the mold therewith when the ingot is stripped.

It will thus be seen that by very simple means I provide a seal which is especially useful where a stripping plug is employed. While the plate is supported on the bottom wall of the mold it also rests on the inner end of the plug B and while the plug may be said to support the plate, yet a close fit should be made between the edge or rim of the plate and bottom walls of the mold.

I claim as my invention:

1. An ingot mold having a bottom opening and a sealing closure for the bottom opening consisting of a plate onto which the metal is poured and which is of larger diameter than said opening and the edge of which rests upon the bottom walls of the mold above the opening therein and seals the mold cavity.
2. An ingot mold having a bottom opening and a necked-in portion provided with a rounded part surrounding the bottom opening and a sealing closure consisting of a plate the edge of which rests upon said rounded portion of the mold walls.
3. An ingot mold having a bottom opening and a necked-in portion at its lower end provided with a rounded portion surrounding the bottom opening and a sealing closure consisting of a plate having a rim engaging said rounded portion and sealing the mold cavity.
4. An ingot mold having a bottom opening and a necked-in portion surrounding the bottom opening provided with a rounded part around said opening, a stripping plug in the bottom opening of the mold and a sealing plate resting on the plug and having a flange engaging said rounded part of the necked-in portion of the mold.

ing, a stripping plug in said opening, a metal sealing plate of larger diameter than the opening and the edge of which engages the mold walls above the bottom opening therein and seals the mold cavity above the 40 plug.

5. An ingot mold having a bottom opening and a necked-in portion surrounding the bottom opening provided with a rounded part around said opening, a stripping plug 45 in the bottom opening of the mold and a sealing plate resting on the plug and having a flange engaging said rounded part of the necked-in portion of the mold.

6. An ingot mold having a bottom opening and a sealing plate onto which the metal is poured and which is of larger area than the bottom opening of the mold which covers the same and is supported by the walls of the lower portion of the mold cavity 55 above the bottom opening.

7. An ingot mold having a necked-in portion and a bottom opening, and a sealing plate of larger area than the bottom opening covering the same and supported on the 60 necked-in portion of the mold.

8. An ingot mold having a bottom opening, a sealing plug mounted therein, and a sealing plate of larger area than the bottom opening supported on the mold walls above 65 said opening and above the plug.

In testimony whereof, I have hereunto subscribed my name.

EMIL GATHMANN.
